DESIGN FOR A SPOON OR SIMILAR ARTICLE

George A. Feinauer, Providence, R. I., assignor
to Gorham Mfg. Co., Providence, R. I.

Application October 11, 1934, Serial No. 53,578

Term of patent 14 years

To all whom it may concern:

Be it known that I, George A. Feinauer of Providence, in the county of Providence and State of Rhode Island, have invented a new, original and ornamental Design for a Spoon or Similar Article of which the following is a specification, reference being had to the accompanying drawing, forming part thereof.

Figure 1 is a front elevation of a spoon, showing my new design.

Figure 2 is a section of the same on the line 2—2 of Figure 1, and

Figure 3 is a rear elevation showing my new design.

The essential feature of the design consists in the elongated upper portion of the handle which is connected to the bowl portion by the short shank.

I claim:

The ornamental design for a spoon or similar article as shown and described.

In testimony whereof I have signed my name to this specification.

GEORGE A. FEINAUER.
